CLAIM

The ornamental design for an adhesive bandage, as shown and described.

DESCRIPTION

FIG. 1 is a top plan view thereof;

FIG. 2 is a right side elevational view, the left side being a mirror image thereof;

FIG. 3 is a bottom plan view thereof;

FIG. 4 is a front elevational view thereof;

FIG. 5 is a rear elevational view thereof; and,

FIG. 6 is a top plan view showing a second embodiment of our new design, the sole difference being in the appearance and design of the background of the adhesive strip.
